US0D1073410S

(12) **United States Design Patent** (10) Patent No.: **US D1,073,410 S**
(45) Date of Patent: ** May 6, 2025

(54) **INSULATED CONTAINER**

(71) Applicant: **Igloo Products Corp.**, Katy, TX (US)

(72) Inventors: **John Maldonado**, Katy, TX (US); **Julie Park**, Cypress, TX (US)

(73) Assignee: **Igloo Products Corp.**, Katy, TX (US)

(**) Term: **15 Years**

(21) Appl. No.: **29/872,119**

(22) Filed: **Mar. 7, 2023**

(51) LOC (15) Cl. **07-10**

(52) U.S. Cl.

USPC **D7/605**; D3/273; D3/294

(58) **Field of Classification Search**

USPC D3/216, 217, 254, 273, 283, 287, 289,

D3/294, 318; D7/605–608, 709–710

CPC ... A45C 11/20; A45C 3/00; A45C 7/00; A47J

47/14; A47J 47/145; F25D 2331/801;

F25D 2331/804

(57) **CLAIM**

The ornamental design for an insulated container as shown and described.

DESCRIPTION

FIG. 1 is an upper perspective view of an insulated container showing our new design;

FIG. 2 is a lower view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the figures illustrate portions of the insulated container that form no part of the claimed design.

1 Claim, 8 Drawing Sheets
